UNITED STATES PATENT OFFICE.

SAMUEL A. GOLDBERG, OF CHICAGO, ILLINOIS.

DESIGN FOR HOSIERY.

Application filed December 15, 1928. Serial No. 29,286. Term of patent 7 years.

To all whom it may concern:

Be it known that I, SAMUEL A. GOLDBERG, a citizen of the United States, residing at Chicago, in the county of Cook and State of Illinois, have invented a new, original, and ornamental Design for Hosiery, of which the following is a specification, reference being had to the accompanying drawing, forming a part thereof.

The design comprises a pair of upstanding tapered projections, one projection being disposed on each side of the fashion line above the heel portion, the upper tapered or pointed ends of said projections terminating in

substantially diamond-shaped head portions. The inner opposed and marginal edges of said projections converge at the fashion line and the outer marginal edge portions of the projections at the base thereof are offset or indented in V-formations.

The figure is a rear perspective view of the stocking showing my new design, a part of the stocking being broken away.

I claim:

The ornamental design for hosiery, as shown and described.

SAMUEL A. GOLDBERG.
